[57] CLAIM

The ornamental design for an electrical outlet protector, as shown and described.

DESCRIPTION

FIG. 1 is an environmental perspective view of an open electrical outlet protector showing my new design; FIG. 2 is an environmental perspective view of a closed electrical outlet protector thereof; FIG. 3 is a front elevational view thereof; FIG. 4 is a right side elevational view with the left side being a mirror image thereof; and, FIG. 5 is a top view with the bottom view being a mirror image. The broken line showing of an electrical receptacle, a plug and two safety plugs in FIG. 1 and an electrical cord in FIGS. 1 and 2 are for illustrative purposes only and forms no part of the claimed design.

FIG. 5

FIG. 4

FIG. 3
